BRIEF BAG CLOSURE MEANS

Samuel Klehr, Newark, N. J.

Application March 21, 1949, Serial No. 82,619

4 Claims. (Cl. 150—1.6)

1

The present invention deals with brief bags and more particularly with brief bags constructed for the utilization of slide fastener means.

In the manufacture of brief bags, hand bags and the like, it is a general practice to employ slide fasteners of known construction as closing and opening means. The fasteners may be stitched or otherwise secured to the article, e. g. brief bag, in the usual manner either longitudinally along an uppermost portion, i. e. the top portion, or along the top portion and extending downwardly therefrom on one or both sides for a distance depending upon the degree of opening desired. It is not particularly desirable to secure the fasteners along the top and completely down both sides because of the inconvenience encountered in opening and closing the bag. It is also disadvantageous to secure the slide fastener only to a top portion because the opening thereby provided is not large enough to conveniently insert or remove the contents of the bag. Therefore, it has been the general practice to secure slide fasteners along the top portion and extending partially down both sides. Various constructions in accordance with the latter practice have been proposed and utilized. Such construction is particularly applicable in the case of hand bags, or articles of luggage having substantial width and capacity, because the opening thereby provided is generally comparable with the width of the bag. In such case the opening is satisfactory. However, in the case of a brief bag, which may be differentiated from a hand bag in that the brief bag is necessarily of more limited capacity and of less width, e. g. a width which gives the bag a substantially flat appearance, such construction offers disadvantages which would not be applicable to hand bags of greater width. Accordingly, an opening in a brief bag comparable to its width is not sufficient for the convenient insertion or removal of contents. There is a tendency, therefore, to force the opening to its fullest extent and thereby exert a strain upon the slide fastener extremities or terminals. This strain upon the slide fastener terminals is detrimental in that the slide fastener thereby becomes damaged and inoperative. Furthermore, the gusset construction of the conventional brief bag is such that the opening of the bag is limited by the distance that the slide fastener extends down the sides of the bag. In order to provide a wider opening, it is customary to extend the slide fastener or "zipper" for a greater distance along the sides. However, this adds to the inconvenience in opening and closing the brief bag and does not eliminate strain on the fastener terminals.

It is one object of this invention to provide an improved brief bag. It is another object of this invention to provide a gusset for brief bags

2

whereby slide fastener terminals are rendered free of strain. It is a further object of this invention to increase the opening of a brief bag without further extending the slide fastener down the sides of the bag. It is a still further object of this invention to provide a brief bag gusset adapted to provide an opening greater than the width of the bag. Other objects and advantages of this invention will become apparent from the description hereinafter following and the drawings, forming part hereof, in which:

Figure 1 is a perspective view of a brief bag according to this invention,

Figure 2 illustrates a lay-out view of the gusset, and

Figure 3 illustrates an enlarged view of a gusset portion.

According to the present invention, the brief bag comprises a gusset construction which allows a slide fastener to be secured to the brief bag along the top portion thereof and partially down both sides. However, the particular construction of the gusset is such that there is no strain exerted upon the slide fastener terminals even when the bag is opened to its fullest extent. Elimination of such strain prolongs the life of the slide fastener. Moreover, the gusset construction not only safeguards the slide fastener but also provides an opening greater than has been heretofore possible without further extending the fastener along the sides of the brief bag. Such advantage is particularly desirable in that the brief bag is not only more conveniently opened and closed, but the contents of the bag are more safely contained therein due to the retention of the depth of the bag, i. e. the gusset portions of the brief bag which comprise two sides are maintained as high as possible so that the contents of the bag are protected against accidental dislodgement from the bag when the bag is opened.

Figure 1 is a perspective view of the brief bag of this invention showing two sides 1 and 2, handles 3 and gusset 4. The handles may be either fixed in carrying position or may be adapted for slideable recession into the apertures 5 for underarm carriage if desirable. The gusset 4 is preferably recessed between the sides 1 and 2 along the perimeters thereof so that it may be protected against wear, etc., by the sides 1 and 2, which may comprise a material of substantial stiffness in combination with suitable resiliency, e. g. leather of appropriate thickness. Slide fastener 6 extends downwardly and inwardly along the gusset 4 so that the terminal 7 is substantially inward of the edges 8 and 9 of sides 1 and 2 respectively. The downward and inward extension of the slide fastener 6 is provided for by the construction of the gusset 4 which is more particularly described hereinafter.

Figure 2 illustrates a lay-out view of the entire gusset of this invention. The gusset 4 is preferably made in three sections. One section comprises the bottom portion 10 and the sides 11 and 12, while the other two sections comprise two strips 13 and 14 which are joined at 15 and 16 and 17 and 18 respectively to form the complete gusset in the manner shown by Figure 1. The broken lines 19 and 20 indicate folds in the gusset which secure inside partitions of the brief bag in the manner shown by Figure 1.

Figure 3 illustrates an enlarged view of one portion of the gusset, e. g. side 11 of the gusset, with a slide fastener 6 secured thereto. The gusset is cut or formed into a specific shape which allows opening of the brief bag to its fullest extent without exerting a strain upon the slide fastener terminal. The cut or shape of the gusset portion 11 along which the slide fastener is secured, is such that it comprises a variably converging bilaterally symmetrical contour. There are two distinct bilaterally symmetrical stages and preferably three such contour stages. One contour stage 21 of the cut comprises an upper portion of a normal V-shaped contour, while a second lower stage 22 of the cut deviates therefrom and curves inwardly and downwardly so that both sides of the cut converge at a point substantially above the apex of a normal V-shaped contour. This construction or cut of the gusset offers at least two advantages. One advantage is that the slide fastener extends a minimum distance along the gusset portion 11 to provide convenience in opening and closing the bag and at the same time provide an opening greater than is possible with a normal V-shaped cut of comparable dimensions. For example, when the bag is opened to its fullest extent, the stage or portion 21 of the cut bends outwardly to provide the large opening. Another advantage is that the stage or portion 22 of the cut, which is slack in the normal closed position of the bag, becomes only slightly taut when the bag is opened to its fullest extent because of the curved contour thereof, and thereby reduces or eliminates any possible strain on the fastener terminal 7. Still another contour stage 23 of the cut is provided to further take up any tension on the terminal 7 should the bag opening be forced beyond a normal maximum opening. This third stage 23 is a continuation of the stage 22 into a rounded junction of the two bilaterally symmetrical sides of the cut and may be substantially U-shaped. In the closed position of the bag, the downward and inward extension of the slide fastener 6, as illustrated by Figure 1 is provided for by the fact that when the portions 21 of the cut meet, the portions 22 and 23 of the cut becomes slack and dispose themselves inwardly of edges 8 and 9 of the sides 1 and 2. Upon the opening of the bag, the portions 22 and 23 of the cut move outwardly or in the direction of the edges 8 and 9.

The broken lines 1a and 2a indicate the approximate positions of sides 1 and 2 respectively and the broken lines 21A indicate the approximate positions of the portions 21 of the cut when the bag is opened to its fullest extent. Since the sides 1 and 2 are preferably composed of a stiff but resilient material, any opening of the bag beyond its width, i. e. the width of the gusset portion 11, will cause the bottom of sides 1 and 2 to move inwardly toward each other. Therefore,

inner partitions secured by the folds 19 and 20 (shown in Figure 1) will automatically become fully extended or opened upon opening of the brief bag and thereby allow convenient insertion of contents into said partitions.

Therefore, the invention, as hereinbefore described, provides improvements in brief bags whereby such brief bags are more conveniently opened and closed and the slide fastener means are safeguarded against damage, etc., by a gusset construction having a bilaterally symmetrical cut of variable convergence along which cut said slide fastener means are secured.

What I claim is:

15. A brief bag adapted to be opened and closed by slide fastener means, comprising a gusset having a bilaterally symmetrical cut of varying convergence along which said slide fastener means are secured, said cut having at least two contour stages of which one stage comprises an upper portion of a V-shaped contour and at least a lower second stage which curves inwardly and downwardly therefrom.
20. A brief bag adapted to be opened and closed by slide fastener means, comprising a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
25. A brief bag adapted to be opened and closed by slide fastener means, comprising in combination two sides composed of a material of substantial stiffness and suitable resiliency, a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
30. A brief bag adapted to be opened and closed by slide fastener means, comprising in combination two sides composed of a material of substantial stiffness and suitable resiliency, a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
35. A brief bag adapted to be opened and closed by slide fastener means, comprising in combination two sides composed of a material of substantial stiffness and suitable resiliency, a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
40. A brief bag adapted to be opened and closed by slide fastener means, comprising in combination two sides composed of a material of substantial stiffness and suitable resiliency, a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
45. A brief bag adapted to be opened and closed by slide fastener means, comprising in combination two sides composed of a material of substantial stiffness and suitable resiliency, a gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
50. A brief bag adapted to be opened and closed by slide fastener means, comprising in combination two sides composed of a material of substantial stiffness and suitable resiliency, a gusset having a bottom portion and two side portions formed from a single section and a top portion formed from two strips joined to said side portions, the side portions of said gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
55. A brief bag adapted to be opened and closed by slide fastener means, comprising in combination two sides composed of a material of substantial stiffness and suitable resiliency, a gusset having a bottom portion and two side portions formed from a single section and a top portion formed from two strips joined to said side portions, the side portions of said gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
60. A brief bag adapted to be opened and closed by slide fastener means, comprising in combination two sides composed of a material of substantial stiffness and suitable resiliency, a gusset having a bottom portion and two side portions formed from a single section and a top portion formed from two strips joined to said side portions, the side portions of said gusset having a bilaterally symmetrical cut of varying convergence along which said slide fastener means are secured, said cut having three contour stages of which one stage comprises an upper portion of a V-shaped contour, a lower second stage which curves inwardly and downwardly therefrom to a substantially U-shaped third stage which terminates said bilaterally symmetrical cut.
